UNITED STATES PATENT OFFICE

ALBERT L. EMENS, OF LA FAYETTE, INDIANA, ASSIGNOR TO DUNCAN ELECTRIC MANUFACTURING COMPANY, OF LA FAYETTE, INDIANA, A CORPORATION OF ILLINOIS

ELECTRICITY-METER COVER FASTENER

Application filed January 11, 1929. Serial No. 331,732.

My invention relates to electricity meters and has for its general object the provision of improved means for securing the body and cover portions of a meter casing in assembly.

5 In carrying out my invention one of the two aforesaid casing portions, preferably the body portion, is equipped with an operating bar which is in controlling relation to a cam which, in turn, is in controlling relation to a holding member that is provided upon the casing portion that carries the bar, this holding member and the other casing portion having complementary parts whereby the two casing portions are held together when the cam controlling bar is suitably actuated. In the preferred embodiment of the invention two diametrically opposite latching hooks are employed, each latching hook being swingingly mounted upon a bolt, each bolt being within 15 the influence of a cam in the region thereof. The cams are desirably integrally formed with the bar and the bar is preferably centrally pivoted upon the back of the body portion of the meter casing so as to turn upon an axis that is coincident with the meter casing axis, this casing preferably being generally cylindrical. A securing device is also desirably provided upon the body portion of the casing for holding the bar in its latching 20 hook applying position. This securing device is preferably in the form of a threaded pin which is screwed into the body portion of the casing to bring the head of the pin into clamping engagement with the rim of a hole in the bar through which the pin is passed. Suitable sealing means are employed for preventing the undetectable removal of such securing pin.

The invention will be more fully explained 40 in connection with the accompanying drawings in which Fig. 1 is a front view illustrating a single phase induction electricity meter equipped in accordance with my invention; Fig. 2 is a sectional view on line 2—2 of Fig. 1, on a larger scale; Fig. 3 is a sectional view on line 3—3 of Fig. 2; Fig. 4 is a sectional view on line 4—4 of Fig. 3; Fig. 5 is a sectional view on line 5—5 of Fig. 3; Fig. 6 is a rear elevation of a portion of the meter; Fig. 50 7 is a sectional view on line 7—7 of Fig. 5;

and Fig. 8 shows some of the parts that are illustrated in Fig. 5 but with parts of the latching mechanism in changed positions.

The meter illustrated is an induction watt-hour meter. This meter is inclusive of an upright spindle or shaft 7 suitably held in bearings at its ends. A horizontal aluminum armature disc 10 is carried by the spindle on which the disc is rigidly secured. This disc is turned proportionately to the energy consumed by the load by a magnet system that is inclusive of a current or series magnet and a pressure or shunt magnet. The current magnet is inclusive of an E shaped core of laminated iron 11 whose middle leg is wound by a coil 12 serially included in one load circuit side. The pressure magnet is inclusive of a U shaped laminated iron core 13 whose legs are surrounded by the coils 14 which are connected in series in the same bridge between the load circuit sides. The speed of the armature of the meter is checked by the damping permanent magnet 15 which is upon one side of the disc 10, a keeper 10' being upon the other side of the disc. The meter parts illustrated and described constitute a meter motor whose armature 10 and spindle 7 turn proportionately to the wattage in a manner well known to those familiar with the art.

The cores of the current and pressure magnets are carried by posts 18 which, in turn, are carried by the upright back wall 19 of the meter casing. The arcuate wall 20 of the meter casing body projects forwardly from the meter back 19 and surrounds the magnets. This casing body is desirably formed of cast-iron. An upright plate 21, of iron, constitutes a magnetic shield which is interposed between the magnet system and the damping magnet. This plate is mounted upon ears 22 that are desirably integrally cast with the meter casing body and are contained within such body. Said plate is nearly coplanar with the front edge of the meter casing. A clip structure, of which a portion 23 is shown, is carried by and upon the front face of the plate 21 and carries the damping magnet 15 in front of said plate. A post 24 is carried by and projects forwardly from the plate 21 and carries the

keeper 10'. A cover 25, preferably of glass, is of cup shape, the rim of the cup being carried upon the front edge of the meter casing body, there being a packing 26 which is clamped between the cover and casing body. 5 The means illustrated for clamping the cover in place is inclusive of two diametrically opposite latching hooks 27. Each of these hooks is swingingly mounted upon the head 10 of a bolt 28. The stems of these bolts are slidingly received in bores that extend along the axis of the meter and are provided in ears 30 that are cast integrally with the body portion of the meter casing. The heads of 15 said bolts are forwardly projected beyond the places of attachment of the latching hooks with the bolts. An actuating bar 31 is journaled upon a bolt 32 that is screwed into the meter back 19 coaxially with the 20 meter casing, said bar being thus adapted to turn in a plane that is normal to the meter casing axis. The ends of the bar 31 are forwardly deflected and enter the recesses 19' in the back of the meter casing. Said bar 25 31 is formed with oppositely inclined portions 33 that form cams upon which the bolt enlargements 28' ride. When said bar is turned in one direction said bolt enlargements are forced to ride upon said cams to 30 the higher portions of the cams whereby rearward movement of said bolts is forced together with a corresponding rearward movement of the latching hooks 27. The cover engaging ends of said latching hooks 35 are thus caused to grip the annular rib 34 of the cover 25, Figs. 2 and 5. The bar 31 is maintained in its latch applying position by means of a pin 39 whose shank is screwed into the body portion of the meter casing 40 and enters the interior of this body portion. The head of the pin 39 is clamped against the outer end of the lateral extension 31' of the bar 31, the shank of the pin 39 passing through an opening formed in this bar extension and the head of said pin being clamped against the part that margins the opening therethrough. Withdrawal of the 45 clamping pin 39 is prevented by the inner end of the holding pin 40 which is screwed into 50 and through the terminal block 41 that constitutes the closure for the opening in the bottom of the casing continuation 20'. The pin 40 is desirably passed through an opening 39' in the inner end of the shank of the screw 39, 55 turning of this screw being thus effectively prevented. As will later appear sealing means are provided to guard against the undetectable withdrawal of the pin 40 from holding engagement with the pin 39. 60 The terminal block 41 formed of insulation carries the four meter terminals 42 that are contained in the meter casing. Contact pins 43 are screwed into the terminals 42. These contact pins have polygonal flanges 44. 65 The terminal block 41 is clamped between the

terminals 42 and the flanges 44 and said terminals are consequently, mounted upon the upper side of said terminal blocks. The pins 43 are received within the contact sleeve 45 with which the line and load circuit sides are connected as is well understood by those familiar with the art. The contact sleeves 45 are mounted upon a terminal block 46, also formed of insulation. The terminal block 46 is mounted upon the ears 47 that are cast integrally with and within the service connection box 48. The terminal block 41 is clamped against the rim that surrounds the open upper end of the service connection box by means of the clamping bolts 49 that are 70 screwed into the ears 20' that are cast integrally upon and within the casing continuation 20'. Said clamping bolts are formed with shoulders 49' which have direct clamping engagement with the block 41. Said bolts 75 are also provided with wing nuts 50 which are screwed upon their outer ends and force the service connection box 48 against the terminal block 41. A skirted cap 51 has its end wall clamped between the terminal block 41 80 and the bottom edge of the meter casing continuation 20'. This cap end wall is formed with a large opening to permit of the clear passage of the meter terminals 42 from the terminal block 41 into the interior of the meter casing. The skirt of said cap surrounds the terminal block 41 and the top rim of the service connection box and desirably extends a considerable distance below said terminal block, whereby access of moisture to the 85 service connection box at the upper end of this box is guarded against. 90

Undetectable access to the interior of the service connection box is prevented by means of the sealed wires 52 which are passed through openings that are formed in the wing nuts 50 and the outer ends of the bolts 49. So long as said sealing wires are unbroken the interengagement of the pins 39 and 40 remains intact. If the service connection box is removed the undetectable removal of the pin 40 is still guarded against by the sealing wire 53 which is passed through the head of the pin 40, that is below the terminal block 41, and through a clip 54 that is clamped 105 between the terminal block 41 and the shoulder 49' of the adjacent clamping bolt 49. The sealing wires 52 and 53 in cooperation with the pin 40 thus effectively guard the pin 39 110 from undetectable removal from its effective position in which it holds the bar 31 in a position in which this lever functions, indirectly, to hold the meter cover in place. While said bar is preferably coaxial with the meter casing in order that it may be turned in a 115 plane that is transverse to the direction of movements of the bolts 28 and hooks 27 the invention is not to be thus limited. 120

Changes may be made without departing from the invention. 125

Having thus described my invention, I claim:

1. The combination with a casing for an electricity meter having body and cover portions; of a plurality of latching hooks, each 5 swingingly mounted independently of the others on one of the portions, and each linearly reciprocable independently of the others with respect to said portion, a bar mounted to turn in a plane transverse to the direction of 10 bodily movement of said latching hooks, and cams operated by said bar and operable upon the latching hooks respectively and simultaneously to effect linear reciprocation of the 15 latching hooks and the holding engagement thereof with the other casing portion.

2. The structure in claim 1 wherein each latching hook is mounted on a bolt which is 20 linearly reciprocable and which is engaged by one of the cams controlled by the bar.

3. The structure of claim 1 wherein a bolt 25 is mounted to slide in the general direction of bodily movement of the latching hook that is mounted thereon and which bolt is engaged by the cam that is controlled by the bar.

4. The structure of claim 1 wherein the cam is carried upon the bar.

5. The structure of claim 1 wherein a positioning pin is employed for holding the bar 30 in a latching hook applying position; and a sealing device is employed for preventing undetectable effective shifting of said pin.

6. The structure of claim 1 wherein a positioning pin is employed for holding the bar 35 in a latching hook applying position; a second pin is screwed into holding engagement with the positioning pin; and a sealing device is employed for preventing undetectable removal of the second mentioned pin.

40 In witness whereof, I hereunto subscribe my name.

ALBERT L. EMENS.
